UNITED STATES PATENT OFFICE.

CHARLES L. McCALLISTER, OF MOSBY, INDIANA.

DESIGN FOR AN AXLE DUST-GUARD.

SPECIFICATION forming part of Design No. 31,641, dated October 10, 1899.

Application filed September 16, 1899. Serial No. 730,774. Term of patent 7 years.

To all whom it may concern:

Be it known that I, CHARLES L. McCALLISTER, a citizen of the United States, residing at Mosby, in the county of Perry and State 5 of Indiana, have invented a certain new and useful Design for an Axle Dust-Guard; and I do declare the following to be a full, clear, and exact description of the invention, such as will enable others skilled in the art to which 10 it appertains to make and use the same, reference being had to the accompanying drawings, and to the letters of reference marked thereon, which form a part of this specification.

15 In the accompanying drawings, Figure 1 is a perspective view of a vehicle-axle dust-guard, showing my novel design; and Fig. 2 is a vertical central longitudinal section of the same.

20 As shown in the drawings, the leading or

essential features of the design consist in a tapering body portion A, terminating at its enlarged end in a cylindrical portion B and at its opposite or smaller end in a smaller extension C, said extension C having a horizontal base D, vertical side walls E, and oval top F, there being provided upon the sides of the said portion C brackets or extensions G.

Having thus described my invention, what I claim to be new, and desire to secure by Letters Patent, is—

The design for a vehicle-axle dust-guard, substantially as herein shown and described.

In testimony whereof I affix my signature in presence of two witnesses.

CHARLES L. McCALLISTER.
